UNITED STATES PATENT OFFICE.

SAMUEL D. COLLETT, OF NEW YORK, N. Y., ASSIGNOR TO ELEVATOR SUPPLY & REPAIR COMPANY, A CORPORATION OF ILLINOIS.

ELEVATOR SIGNAL DEVICE.

SPECIFICATION forming part of Letters Patent No. 700,619, dated May 20, 1902.

Application filed February 10, 1902. Serial No. 93,300. (No model.)

To all whom it may concern:

Be it known that I, SAMUEL D. COLLETT, a citizen of the United States, residing at New York, State of New York, have invented certain new and useful Improvements in Elevator Signal Devices, of which the following is a clear, full, and exact description.

My invention relates to a signal mechanism for elevators; and my object is to provide a device by which the "starter" may give a signal to the operator in any of the elevator-cars and independently of the other cars.

My invention will be defined in the claims.

The drawing shows diagrammatically one embodiment of my invention.

In tall buildings provided with a number of elevators it is customary to have an attendant at the ground-floor to tell the operator of the car when to start the same upward, so that the cars will run at regular intervals. It often happens, however, after a car has started or when a car is at the top of the shaft that the starter wishes to recall the car or hurry the car on its way, and it is desirable that the starter should be able to communicate with each car, so that he can control their movement after they have left the "starting-floor." In the embodiment of my invention shown in the drawing I have provided an electrically-operated signal in each car and a relatively independent normally open signal-actuating circuit to each car and a normally open switch in each signal-circuit located at the lower floor, by which the starter may close any one of these circuits at will and give prearranged signals to the operator of any car, preferably whenever the car may be in the shaft at that time.

In the preferred embodiment of my invention illustrated in the drawing I have shown a building provided with only two cars; but it will be obvious that its chief application will be in buildings having a greater number.

1 and 2 are the elevator-cars at rest at the starting-floor, usually the ground-floor. Each elevator-shaft may be provided with lights 3 4 or 5 6 outside of the shaft on each floor, and a normally open push-button switch 7 on each floor controls the circuits to these 50 lamps. A lamp 8 may be provided in each

car to signal the operator to stop at the floor the car is then approaching.

The brush 9 and stationary contact-plates 10 to 21 indicate part of a commutator mechanism, which may be located at any convenient place for changing the circuits and making and breaking connections, as is well known in the art. This brush 9 may be provided with contact-blocks 22 to 27, (indicated in dotted lines) and electrically connected, as shown. 55 This brush is moved over the stationary contact-plates 10 to 15 correspondingly with the movement of the elevator in the manner well known in the art. The plates 16 to 21 are understood to be provided with a similar brush 65 moving correspondingly with the car 2.

28 is a suitable source of electromotive force—a battery of a low electromotive force, for example.

29 is a mercury-pot, and 30 is a pivoted 70 switch-finger which makes and breaks connection with the mercury.

31 is a spring-actuated pivoted releasing-lever which normally holds the lever 30 in its raised position, as shown.

75 32 is an electromagnet for drawing lever 31 to the left to release lever 30, and 33 is a magnet for drawing down the left end of lever 30 to the position shown. When the button 7 is pushed, the circuit through the coils of 80 magnet 32 is closed, energizing said magnet and releasing lever 30, the end of which falls and dips into the mercury-pot, partially closing the lamp-circuits.

It will be understood that contact-plates 85 and switch devices will be provided for each floor; but I have in the drawing shown only those for one floor and which are used when the car is moving upwardly. As the car 1 passes the third floor, for example, the contact-blocks 23 and 24 contact with the plates 11 and 12, and if the "up" button 7 on the fifth floor has been pushed a circuit will then be completed from dynamo 34 through up lamp 3, plates 11, 12, and 15, mercury-pot 29, 90 and lever 30 back to the dynamo. Contact-plate 15 will not be engaged by block 27 until the car has reached the fourth floor, when a circuit is closed from the dynamo through lamp 8 in the car, plate 13, blocks 25 and 27, 95 100

and plate 15 back to the dynamo through the mercury-pot. This will light the lamp 8 and cause it to signal the operator to stop the car at the next floor above. Block 26 contacts 5 with plate 14 as the car starts to move away from the fifth floor, at which the passenger has been taken on, and closes a circuit from battery 28 through a normally closed "transfer-button" switch 35, plate 10, blocks 22 and 10 26, plate 14, and coils of magnet 33. This energizes magnet 33, raising lever 30 from pot 29 and breaking the lamp-circuits. If the transfer-button switch 35 is opened before and until after plate 14 and block 26 are in 15 contact, the circuit through the coils of magnet 33 will not be closed and the lamp-circuits through the mercury-pot will remain partially closed, as before, and as the commutators for the other cars are suitably cross-connected—for example, as shown—the up lamps 6 and 8' of the next following car will be lighted as that car approaches.

39 represents a liquid or other indicator for 25 each car at the starting-floor for showing the starter the position of each car at all times in its travel. It will be understood that any well-known device may be provided for actuating the same.

In a building having a large number of cars 30 a starting attendant is usually posted at the ground-floor to keep the cars running regularly, and it is desirable that he be able to communicate with each car operator independently of the others, preferably at all 35 times, so that the starter can hurry a car down or recall it or start it from the top floor, so as to keep the service uniform. In order to accomplish this, I have provided a signal on each car—such, for example, as a buzzer 40—and a circuit to each, independent of the 40 buzzer-circuits to the other cars, and means located at the starting-floor for controlling these independent circuits. In the embodiment of my invention shown in the drawing I have 45 provided a connection 37 from battery 28 running to the starting-floor and branch circuits in parallel to each car through the buzzers therein. These relatively independent circuits preferably have in each a normally 50 open spring-actuated push-button switch 38 at the starting-floor by which the starter may close any one of the buzzer-circuits, and thus operate the buzzer in any car at will and independently of the buzzers on the other cars. 55 The buzzer is an audible signal, and the operator will therefore not confuse it with the signal-lamp 8, and his attention will be called by it whether he is in the car or not. The buzzer obviously makes the signal only so 60 long as its circuit is closed. I preferably complete the buzzer-circuit back to the battery by tapping it into the transfer-button circuit, as shown, so that in this embodiment only one additional wire in each car-cable need be provided.

65 It will be obvious that many variations from the construction illustrated may be made

without departing from my invention as claimed, and I therefore do not limit myself to the embodiment heretofore shown and described.

What I claim is—

1. In a building having a plurality of floors in combination, a plurality of elevator-cars passing said floors, a relatively independent 75 circuit to each car, a signal on each car controlled by the circuit to that car, and means located at the "starting-floor" and controlling said independent circuits, whereby the signal on any car may be operated from said floor and independently of the signals on the other cars.

2. In a building having a plurality of floors in combination, a plurality of elevator-cars passing said floors, a relatively independent 85 and normally open circuit to each car, a signal on each car controlled by the circuit to that car and operative on the closing of its circuit, and means located at the "starting-floor" and controlling said independent circuits, whereby the signal on any car may be operated from said floor and independently 90 of the signals on the other cars.

3. In a building having a plurality of floors in combination, a plurality of elevator-cars 95 passing said floors, a relatively independent and normally open circuit to each car, a signal on each car controlled by the circuit to that car and operative on the closing of its circuit, and a switch in each circuit located 100 at the "starting-floor" for closing said independent circuits, whereby the signal on any car may be operated from said floor and independently of the signals on the other cars.

4. In a building having a plurality of floors in combination, a plurality of elevator-cars 105 passing said floors, a relatively independent and normally open circuit to each car, a signal on each car controlled by the circuit to that car and operative on the closing of its 110 circuit, said signal being "made" only so long as its circuit is closed, and a switch in each circuit located at the "starting-floor" for closing said independent circuits, whereby the signal on any car may be operated 115 from said floor and independently of the signals on the other cars.

5. In a building having a plurality of floors in combination, a plurality of elevator-cars passing said floors, a relatively independent 120 circuit to each car, an audible signal on each car controlled by the circuit to that car, and means located at the "starting-floor" and controlling said independent circuits, whereby the signal on any car may be operated 125 from said floor and independently of the signals on the other cars.

6. In a building having a plurality of floors in combination, a plurality of elevator-cars passing said floors, a source of electromotive 130 force, a relatively independent circuit to each car in parallel from said source of electromotive force, a signal on each car controlled by the circuit to that car, and means located at

the "starting-floor" and controlling said independent circuits, whereby the signal on any car may be operated from said floor and independently of the signals on the other cars.

5 7. In a building having a plurality of floors in combination, a plurality of elevator-cars passing said floors, a relatively independent circuit to each car, a signal on each car controlled by the circuit to that car, and means 10 located at the "starting-floor" and controlling said independent circuits, whereby the signal on any car may be operated from said floor wherever said cars may be in their travel and independently of the signals on the other 15 cars.

8. In a building having a plurality of floors in combination, a plurality of elevator-cars passing said floors, a relatively independent circuit to each car, a signal on each car controlled by the circuit to that car, and means 20 located at the "starting-floor" and controlling said independent circuits, whereby the signal on any car may be operated from said floor and independently of the signals on the 25 other cars, and signal devices also at the "starting-floor" automatically indicating the location of the different cars in their travel.

9. In a building having a plurality of floors in combination, a plurality of elevator-cars 30 passing said floors, each of said cars being provided with a signal to indicate an intending passenger, means located at different floors to cause said signals to be operated, a relatively independent and normally open

circuit to each car, a second signal on each 35 car controlled by the circuit to that car and operative on the closing of its circuit, said latter signal being "made" only so long as its circuit is closed, and means located at the "starting-floor" and controlling said independent circuits, whereby a signal may be 40 transmitted from said floor to any of said cars independently of the other cars.

10. In a building having a plurality of floors in combination, a plurality of elevator-cars 45 passing said floors, each of said cars being provided with a signal to indicate an intending passenger, means located at different floors to cause said signals to be operated, a relatively independent and normally open 50 circuit to each car, a second signal on each car controlled by the circuit to that car and operative on the closing of its circuit, said latter signal being "made" only so long as its circuit is closed, and means located at the 55 "starting-floor" and controlling said independent circuits, whereby a signal may be transmitted from said floor to any of said cars independently of the other cars, and signal devices also located at the "starting-floor" 60 and visible to the starter, for visibly indicating at all times the location of each car.

Signed at New York, N. Y., this 6th day of February, 1902.

SAMUEL D. COLLETT.
